BRAKE SHOE

Maurice N. Trainer, East Orange, N. J., assignor
to American Brake Shoe Company, New York,
N. Y., a corporation of Delaware

Application August 9, 1943, Serial No. 497,887

13 Claims. (Cl. 188—258)

1

This invention relates to brake shoes of the kind which have ductile metal reenforcements embedded at the backs of the cast bodies thereof, such shoes being employed on railway and like equipment to effect deceleration thereof.

The ductile metal reenforcement that is included in such a brake shoe, while being effective to resist fracture of the cast body of the shoe, is particularly effective, in the event of fracture of the cast body in the course of use of the shoe, to avoid separation of fractured parts one from the other and from the reenforcement. Such a reenforcement also resists straightening of the arcuate face of the shoe in which it is included, especially when the shoe is heated as an incident to the dissipation of energy in the course of a deceleration effected by forcibly applying the shoe to a moving member and such a reenforcement also assists in dissipating the stresses impressed on the shoe in the course of such a deceleration. In order that such a ductile metal reenforce may effectively accomplish the above enumerated and related functions it is essential that separation between such a reenforce and the cast body of the shoe in which it is included be effectively resisted, particularly in the event of fracture of the body, and it is also important, in the event of such fracture, to prevent movement of the fractured parts relative to each other and the reenforce, and to enable these and related functions to be realized in a novel and effective manner is the primary object of this invention.

It has been observed, in some instances where the cast body of a brake shoe including a reenforce of the character to which this invention pertains has been factured, that a portion of the fractured body is sometimes freed from adjacent portions of the body and from the reenforce so that it falls away from the shoe while other fractured portions of the body are retained in position by reason of the connection of such portions to the reenforce. In some instances such a retained and connected portion may sometimes be so freed from other portions of the body that it is capable of movement relative to other portions of the body metal along the reenforce. In such circumstances and in the course of use of the shoe, such a freed and movable portion sometimes exerted a hammering action on the reenforce and particularly on other portions of the body and because this is quite objectionable it has been the practice to remove and replace such a fractured shoe long prior to the time expected service has been realized from the shoe. There-

2

fore, yet another object of my invention is to effectively prevent movement of fractured portions of the cast body relative to each other and the reenforce in a brake shoe in the event of fracture of the body metal of the shoe and an object related to the foregoing is to so constitute and arrange the reenforce included in a brake shoe it will be effective to prevent relative movement of fractured parts of body metal of the shoe with respect to each other and the reenforce in the event of fracture of the body metal in the course of use of the shoe and particularly in those instances where a portion of the fractured body metal falls away from the shoe.

15 A brake shoe of the character to which this invention pertains and in which the novel reenforce of the present invention is included is usually applied to the peripheral or tread portion of a wheel and therefore embodies an arcuate wearing face that is complementary to such peripheral portion of the wheel. The ductile metal reenforce that is included in such a shoe at the back thereof usually embodies an arcuate configuration of such nature that the reenforce lies in at least 20 substantially parallel relation with the arcuate wearing face of the shoe. Furthermore, when the arcuate wearing face of such a shoe is applied to the tread of the wheel to effect deceleration of the wheel, appreciable stresses are impressed upon the shoe and the reenforce included 25 therein particularly circumferentially of the arcuate wearing face of the shoe and the arcuate configuration of the reenforce. Therefore, yet another object of this invention is to afford an 30 interconnection between the cast metal body of a brake shoe and the ductile metal reenforce included therein which will be effective to resist the stresses impressed on the shoe and reenforce as aforesaid; and an object ancillary to the foregoing is to effectively resist any tendency toward 35 separation between a ductile metal reenforce and the cast body of the shoe in which it is included that may arise as an incident to stresses impressed on the shoe circumferentially of the arcuate wearing face of the shoe.

40 A ductile metal reenforce of the character in which my invention may be advantageously embodied is disclosed in Pogue Patent No. 2,035,720, patented March 31, 1936. The ductile metal reenforce to which this patent relates embodies depressed marginal portions along opposite edges thereof whereby the medial portion of the reenforce is disposed above such depressed marginal portions so as to in effect afford a channel between the depressed marginal portion and be-

neath the medial portion of the reenforce. Re-enforcements of this character have been used extensively and have effectively performed their intended functions. However, in the course of use of brake shoes embodying reenforcements of this nature it has been observed that in some instances it would be advantageous to interlock such a reenforce with the cast metal body of the shoe in which it is included particularly transversely thereacross and so to do is yet another object of this invention. An object ancillary to the foregoing is to afford an interconnection between a reenforcement of the character disclosed in the aforesaid Pogue patent and the cast metal body of the shoe in which it is included that will effectively resist any tendency toward separation between the reenforce and the cast metal body, especially insofar as this may arise by reason of stresses impressed on the shoe circumferentially of the arcuate wearing face thereof.

A ductile metal reenforcement or reenforcement plate of the character to which this invention pertains, which is commonly called a steel back and which includes depressed marginal portions along opposite edges thereof, may be effectively interconnected with the cast metal body of a shoe in which it is included, so as to prevent movement of fractured portions of the cast body relative to each other and the reenforcement, by extending formed portions transversely across the reenforce with respect to the depressed marginal portions thereof. Moreover, when such formed portions are properly related and disposed, thrust impressed on the shoe circumferentially of the wearing face thereof may be impressed on such formed portions so as to thereby be effectively resisted. Hence, yet another object of this invention is to form and relate transversely extending portions on a reenforce plate of the aforesaid character in such a manner that movement of fractured parts of the body of the shoe in which the plate is included relative to each other and the plate will be prevented and also so that thrust impressed on the shoe circumferentially of the arcuate wearing face thereof will be effectively resisted.

Further objects are to afford pockets in a reenforce of the aforesaid character into which portions of the cast body metal of a shoe may be extended; to so locate and relate such pockets that the anchorage of portions of the body metal therein will be effective to resist any tendency toward separation that might arise between the body metal and the reenforce when circumferential thrust of the nature referred to hereinabove is impressed on the shoe; and to so locate and relate such pockets that the portions of the body metal anchored therein will be effective to prevent movement of fractured parts of the body relative to each other and the reenforce in the event of fracture of the body.

Yet other objects are to form pockets in the depressed marginal portions along opposite edges of a reenforce plate and into which pockets portions of the cast body metal may be extended to be anchored therein; to extend ribs between the depressed marginal panels of a reenforce so as to thereby afford pockets beneath the medial part of the reenforce; and to so arrange the reenforce and pockets or ribs of the aforesaid character that these may be afforded in the reenforce by being rolled thereinto in the course of production thereof so as to thereby enable economical production of the reenforce.

Other and further objects of the present inven-

tion will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,

Fig. 1 is a side view, partly in elevation and partly in section, of a brake shoe embodying my invention;

Fig. 2 is a plan view of the ductile metal reenforce that is embedded at the back of the shoe shown in Fig. 1, the body metal that is to be cast about such a reenforce being shown in broken lines;

Fig. 3 is a fragmentary plan view of the back shown in Fig. 2 prior to the time an arcuate configuration is imparted thereto;

Fig. 4 is a fragmentary view of the reenforce as it is illustrated in Fig. 3 and showing the face thereof opposite to that shown in Fig. 3;

Figs. 5 and 6 are transverse sectional views taken substantially and respectively on lines 5—5 and 6—6 in Fig. 1;

Fig. 7 is a view similar to Fig. 1 showing a modified form of my invention;

Fig. 8 is a view similar to Fig. 2 and showing the reenforce that is included in the shoe shown in Fig. 7;

Figs. 9 and 10, respectively, are views corresponding to Figs. 3 and 4 but showing the reenforce illustrated in Figs. 7 and 8; and

Figs. 11 and 12 are transverse sectional views taken substantially and respectively on the lines 11—11 and 12—12 on Fig. 7.

The form of my invention shown in Figs. 1 to 6, inclusive, of the accompanying drawings is embodied in a brake shoe that includes a body 20, preferably of cast iron in which, in accordance with well understood practices in the art, chilled sections may be afforded particularly at the ends and adjacent to the wearing face of the resulting brake shoe. If desired, an expanded metal or other reenforce (not shown) may be included in the body 20. A ductile metal reenforce 21, commonly referred to as a steel back, is embedded in the back of the cast body at the face thereof opposite the arcuate wearing face of the shoe. This back or reenforce is desirably so sized as to terminate in spaced relation with opposite ends of the body 20, the end portions of the back or reenforce plate desirably being disposed beneath end stops 22 provided on the back of the body at ends thereof as is customary in the art.

My invention primarily has to do with the ductile metal reenforce plate or steel back as 21 which is desirably hot rolled to have the desired configuration and characteristics imparted thereto. Moreover, in the course of production of the back as 21, openings as 23 and 24 are formed therein. The body metal flows into such openings during the casting operation whereby the back and body metal are interconnected.

A center attaching lug L is provided on the back of the shoe midway between the ends thereof and includes a ductile metal strap 25 about parts of which portions of the body metal 26 are cast. As best shown in Fig. 1, the strap 25 is substantially U-shaped and has reduced portions

or tongues as 26 projected from the free ends of the limbs thereof, these tongues as 26 being passed through openings as 27 formed in the back or reenforce plate 21 and, as best shown in Figs. 2 and 5, the tongues as 26 are folded over onto and clenched against the under side of the reenforce plate 21 so that the shoulders as 28, Fig. 1, on the strap are clenched against the upper face of the reenforce plate 21 and thereby the strap as 25 is firmly connected to the back or reenforce plate 21 and thereby undesired relative movement between these two elements is prevented.

My improved reenforce plate or steel back 21 is desirably hot rolled from a strip of a width corresponding to the desired width of the reenforce. In this hot rolling operation the depressed marginal panels or flanges 28 and 29 are rolled onto the reenforce along opposite longitudinal marginal edges thereof. By reason of the depressed marginal panels as 28 and 29, the lower face of the center panel or medial part 30, Fig. 5, of the reenforce 21 is disposed to lie above the lower faces of the flanges 28 and 29 and substantially in the plane of the upper faces of these flanges. In this way a channel C is afforded in the reenforce plate beneath the panel 30. As best shown in Figs. 5 and 6, portions of the body metal flow into this channel during the casting operation and the portions of the body metal disposed in this channel effectively interconnect the reenforce 21 and the body 20. Such interconnection is effective to assist in the dissipation of whatever thrust may be impressed upon the shoe, including such a reenforce, transversely across the wearing face of the shoe.

It has been explained hereinabove that it is desirable to insure that a firm interconnection be afforded between the body as 20 and the reenforce plate as 21. This interconnection is desirably of such nature as to effectively resist thrust that is impressed upon the shoe circumferentially of the wearing face thereof and also this interconnection is to be such as to prevent movement of fractured parts of the body relative to each other and the back or reenforce in the event of fracture of the body. To this end, in the course of rolling the depressed marginal portions or flanges 28 and 29 on the reenforce, pockets 31 and 32 are respectively rolled into these flanges so that, as best shown in Fig. 1, portions of the body metal may flow into these pockets during the casting operation. Desirably, the pockets as 31 and 32 are so rolled into the flanges 28 and 29 that the outer faces of the upper parts of pockets are disposed at least substantially in the plane of the upper face of the panel 30. The pockets as 31 and 32 extend transversely across the flanges 28 and 29 and therefore the portions of the body metal which are anchored therein assist in dissipating whatever stresses are impressed upon the shoe circumferentially of the arcuate wearing face thereof.

Moreover, the pockets as 31 and 32 are so spaced one from the other along the extent of the flanges or panels 28 and 29 and these pockets are so located relative to each other that, in the event of fracture of the cast body in the course of use of the shoe in which the reenforce is included, and particularly if some of the fractured portions of the body are retained while others fall away from the reenforce and the shoe, the retained portions of the body will be held against movement relative to each other and the reenforce and thereby a detrimental hammering or pounding action by the retained portions of the body

will be prevented. Hence, a shoe equipped with the novel reenforce plate of the present invention may be retained in service and will function in a satisfactory manner even though the body thereof is fractured in the course of use of the shoe.

Another form of my invention is illustrated in Figs. 7 to 12, inclusive, and the shoe and reenforce illustrated therein are similar to those illustrated in Figs. 1 to 6 and where elements appear in Figs. 7 to 12, inclusive, that correspond to elements illustrated in Figs. 1 to 6, these elements in Figs. 7 to 12 are designated by the same reference character as that employed in Figs. 1 to 6 but the suffix "a" is added to these reference characters where they appear in Figs. 7 to 12.

Thus as in the reenforce as 21, depressed marginal portions or flanges 28a and 29a are rolled into the reenforce 21a shown in Figs. 7 to 12, whereby a channel Ca is provided beneath the central panel 30a of this reenforce. In this instance, however, instead of rolling pockets as 31 and 32 into the depressed flanges 28a and 29a, ribs as 33 are rolled into the reenforce plate 21 to extend beneath the inwardly disposed faces of the flanges and the inclined portions which interconnect these flanges to the center panel 30. Desirably the exposed faces of the ribs 33 are disposed to lie at least substantially in the plane of the lower faces of the flanges 28a and 29a.

As best shown in Figs. 7, 9 and 10, the ribs 33 are provided at spaced intervals along the extent of the channel Ca and in cooperation with the inwardly disposed faces of the depressed marginal portions or flanges 28a and 29a, and the inclined portions which connect these marginal portions or flanges with the center panel 30a, afford pockets P into which portions of the body metal may flow during the casting operation. Those portions of the body metal which flow into and become anchored in these pockets as P are effective to assist in dissipation of stresses impressed on the shoe circumferentially of the arcuate wearing face thereof, the ribs as 33 also assisting in the dissipation of such stresses. Moreover, those portions of the cast body that are anchored in the pockets as P are effective to prevent undesired movement of portions of the body metal relative to each other and the reenforce plate in the event of fracture of the body metal so as to thereby avoid the undesired hammering action to which reference has been made hereinabove.

It will be understood that the provision of pockets as 31 and 32 or ribs as 33 will be effective to prevent undesired movement of portions of the body metal relative to each and the reenforce plate, in the event of fracture of the body metal, whether or not openings as 23 and 24 or 23a and 24a are provided. However, the positions of the ribs as 33 and the pockets as 31 and 32 are advantageously related to the positions of openings as 23 and 24 and 23a and 24a for thereby the positions of the cast body anchored in these openings are effective to assist the ribs or pockets and the body metal anchored therein in the performance of the hereinabove described functions of these elements.

By reason of the provision of pockets as 31 or 32, or pockets as P and the transverse ribs as 33, a firm interconnection is afforded between the reenforce plate or steel back of this invention and the body metal of the shoe in which it is included. Furthermore, such pockets and ribs are effective to prevent undesired movement of

portions of the body metal relative to each other and the reenforce, in the event of fracture of the body metal. Therefore, detrimental hammering by retained but freed portions of fractured body metal may be avoided. Moreover, the provision of pockets as 31 and 32 or pockets as P and ribs as 33 affords an arrangement which is effective to dissipate the stresses that are impressed on the arcuate wearing face of a shoe in which a reenforce embodying such elements is included and this arrangement is effective to prevent undesired separation between the reenforce and the body metal even if the body should be fractured in the course of use of the shoe. Therefore, an arrangement such as that described hereinabove enables the hereinabove set forth and related objects of this invention to be realized.

While I have illustrated and described selected embodiments of my invention, it is to be understood that these are capable of variation and modification and I therefore do not wish to be limited to the precise details set forth but desire to avail myself of such changes and alterations as fall within the purview of the following claims.

I claim:

1. A brake shoe having a cast body and including an arcuate wearing face, a reenforce plate embedded in the body at the back thereof, and a center attaching lug, said plate having flanges along opposite edges that are extended toward said wearing face, and said plate having pockets formed therein facing toward the center of curvature of said wearing face and including wall portions extended transversely of said plate which at least in part are disposed beneath the face of said plate disposed toward the center of curvature of said wearing face, said pockets being spaced one from the other longitudinally of said plate whereby portions of the body metal may be anchored therein to prevent movement of retained portions of the body relative to each and the reenforce plate in the event of fracture of the body in the course of use of the shoe and to assist in the dissipation of stresses impressed circumferentially on the arcuate wearing face of the shoe.

2. A brake shoe having a cast body and including an arcuate wearing face, a reenforce plate embedded in the body at the back thereof, and a center attaching lug, said plate having flanges along opposite edges that are extended toward said wearing face, and said plate having pockets formed wholly in said flanges that open toward said wearing face and which include wall portions extended transversely of said plate which at least in part are disposed beneath the face of said plate disposed toward said wearing face, said pockets being spaced one from the other longitudinally of said plate whereby portions of the body metal may be anchored therein to prevent movement of retained portions of the body relative to each and the reenforce plate in the event of fracture of the body in the course of use of the shoe and to assist in the dissipation of stresses impressed circumferentially on the arcuate wearing face of the shoe.

3. A brake shoe having a cast body and including an arcuate wearing face, a reenforce plate embedded in the body at the back thereof, a center attaching lug, said plate having flanges along opposite edges that are extended toward said wearing face, and ribs on said plate disposed between said flanges to define pockets opening toward said wearing face and in which portions

of the body metal may be anchored to prevent movement of retained portions of the body relative to each and the reenforce plate in the event of fracture of the body in the course of use of the shoe and to assist in the dissipation of stresses impressed circumferentially on the arcuate wearing face of the shoe.

4. A brake shoe having a cast body and including an arcuate wearing face, a reenforce plate embedded in the body at the back thereof, and a center attaching lug, said plate including depressed marginal flanges along opposite edges thereof and a center panel which has the lower face thereof disposed above the lower faces of said flanges, and said plate having pockets formed therein which open toward said wearing face and which include wall portions extended transversely of said plate which at least in part are disposed beneath the face of said plate disposed toward said wearing face, said pockets being spaced one from the other longitudinally of said plate whereby portions of the body metal may be anchored therein to prevent movement of retained portions of the body relative to each and the reenforce plate in the event of fracture of the body in the course of use of the shoe and to assist in the dissipation of stresses impressed circumferentially on the arcuate wearing face of the shoe.

5. A brake shoe having a cast body and including an arcuate wearing face, a reenforce plate embedded in the body at the back thereof, and a center attaching lug, said plate including depressed marginal flanges along opposite edges thereof and a center panel which has the lower face thereof disposed above the lower faces of said flanges, and said plate having pockets formed wholly in said flanges which open toward said wearing face and which include wall portions extended transversely of said plate which at least in part are disposed beneath the face of said plate disposed toward said wearing face, said pockets being spaced one from the other longitudinally of the plate whereby portions of the body metal may be anchored therein to prevent movement of retained portions of the body relative to each and the reenforce plate in the event of fracture of the body in the course of use of the shoe and to assist in the dissipation of stresses impressed circumferentially on the arcuate wearing face of the shoe.

6. A brake shoe having a cast body and including an arcuate wearing face, a reenforce plate embedded in the body at the back thereof, a center attaching lug, said plate including depressed marginal flanges along opposite edges thereof and a center panel which has the lower face thereof disposed above the lower faces of said flanges, and ribs on the lower face of said center panel and disposed transversely of the plate between said flanges and defining pockets which open into the lower face of said plate and in which portions of the body metal may be anchored to prevent movement of retained portions of the body relative to each other and the reenforce plate in the event of fracture of the body in the course of use of the shoe and to assist in the dissipation of stresses impressed circumferentially on the arcuate wearing face of the shoe.

7. A brake shoe having a cast body and including an arcuate wearing face, a reenforce plate embedded in the body at the back thereof, a center attaching lug, said plate including depressed marginal flanges along opposite edges thereof and a center panel which has the lower face thereof disposed above the lower faces of

said flanges, and ribs on the lower face of said center panel and extended between said flanges and cooperating therewith and with the lower face of said center panel to afford pockets in which portions of the body metal may be anchored to prevent movement of retained portions of the body relative to each and the reenforce plate in the event of fracture of the body in the course of use of the shoe and to assist in the dissipation of stresses impressed circumferentially on the arcuate wearing face of the shoe.

8. A reenforce plate for a brake shoe or the like embodying a concavo-convex configuration between opposite edges thereof, and flanges along other opposite edges of said plate that are extended toward the center of curvature of the concave face, said plate having pockets formed therein which open toward the center of curvature of the concave face thereof at spaced intervals along the extent of such plate and which include wall portions extended transversely of said plate and which at least in part are disposed beneath the face of said plate disposed toward said center of curvature.

9. A reenforce plate for a brake shoe or the like embodying a concavo-convex configuration between opposite edges thereof, and flanges along other opposite edges of said plate that are extended toward the center of curvature of the concave face, said plate having pockets formed wholly in said flanges which open toward the center of curvature of said plate at spaced intervals along the extent of said plate and which include wall portions extended transversely of said plate and which at least in part are disposed beneath the face of said plate disposed toward said center of curvature.

10. A reenforce plate for a brake shoe or the like embodying a concavo-convex configuration between opposite edges thereof, flanges along other opposite edges of said plate that are extended toward the center of curvature of the concave face, and ribs on the concave face of

said plate disposed transversely between said flanges and defining pockets which open toward the center of curvature of said plate at spaced intervals along the extent of such plate.

5 11. A reenforce plate for a brake shoe or the like embodying a concavo-convex configuration between opposite edges thereof, flanges along other opposite edges of said plate that are extended toward the center of curvature of the concave face, and ribs on the concave face of said plate disposed between said flanges and cooperating therewith and with the concave face of said plate to afford pockets which open toward the center of curvature of said plate at spaced intervals along the extent of such plate.

10 12. A reenforce plate for a brake shoe or the like embodying a concavo-convex configuration between opposite edges thereof, and flanges along other opposite edges of said plate that are extended toward the center of curvature of the concave face whereby a center panel is afforded on said plate which has the concave face thereof disposed inwardly of said flanges, and ribs on the concave face of said center panel and extended transversely between said flanges and defining pockets which open toward the center of curvature of said plate at spaced intervals along the extent of such plate.

15 13. A reenforce plate for a brake shoe or the like embodying a concavo-convex configuration between opposite edges thereof, and flanges along other opposite edges of said plate that are extended toward the center of curvature of the concave face whereby a center panel is afforded on said plate which has the concave face thereof disposed inwardly of said flanges, and ribs on the concave face of said center panel and extended between said flanges and cooperating therewith and with the concave face of said plate to afford pockets which open toward the center of curvature of said plate at spaced intervals along the extent of such plate.

MAURICE N. TRAINER.
